UNITED STATES PATENT OFFICE.

WILLIAM MILLWARD, OF PITTSBURGH, PENNSYLVANIA.

METALLURGICAL FURNACE.

Application filed July 31, 1922. Serial No. 578,585.

To all whom it may concern:

Be it known that I, WILLIAM MILLWARD, residing at Pittsburgh, in the county of Allegheny and State of Pennsylvania, have invented certain new and useful Improvements in Metallurgical Furnaces, of which the following is a specification.

This invention relates to open hearth or other regenerative furnaces. Furnaces of this type heretofore have been constructed with air and gas ports at or near each end thereof. These ports, particularly the gas port, have always been a source of trouble and annoyance and required close application and watching for the reason that they rapidly burn out and it is and was a common occurrence to have them collapse and fall in. Therefore, it is a principal object of my invention to eliminate entirely all these difficulties by providing a new and novel roofless port furnace of this type which is highly efficient, practical and durable. The above and other features of novelty, advantages and capabilities will become apparent from a detailed description of the accompanying drawings in which I have illustrated one form of my invention, but the construction there shown is to be understood as illustrative only, and not as defining the limits of my invention.

Figure 1 is a vertical sectional view of a portion of an open hearth regenerative furnace, embodying one form of my invention and Fig. 2 is a transverse sectional view taken substantially on the line 2--2 of Fig. 1, looking in the direction indicated by the arrow.

Referring to the drawings in detail, while I have only shown one end of the furnace, the other end in practice will be substantially identical and as is well known to those skilled in the art, this furnace in practice, as is common to all open hearth furnaces, is provided with the usual gas and air checker chambers, and the usual reversing valve mechanism for reversing the flow of air and gas and products of combustion through the furnace.

I have entirely disposed of the usual air and gas ports in each end of the furnace, leaving the entire end of the furnace open and substituted in lieu of the old troublesome air and gas ports a comparatively small block 10, extending across the furnace provided with a semi-elliptical cavity or de-

pression 11, concentric with the axis of the furnace which chamber from a point intermediate its ends extend downwardly and outwardly, discharging into the melting chamber 12 of the furnace. The opposite end of the depression 11 is likewise downwardly and outwardly inclined, but more abruptly and opens into the air uptake 13 leading from the air slag pocket 14 through which flue and slag pocket the regenerated or pre-heated air is admitted. The gas flue 16 leads from a checker chamber, not shown, and admits the pre-heated gas to the goose neck 17 which goose neck is provided with a nozzle 18 set at such a position as to cause the flame from the gas inlet to envelop the bottom and lower portion of the sides of the intake end of the chamber 10 overlapping the edges in such a manner so that no air is admitted from the air uptake 13 at the bottom or lower portion of the sides of the depression 11, thus forcing all the air from said uptake to pass on the top of the flame and hold it down against the metal in the bath and away from the roof.

In order to afford a major pressure to the gas or flame being discharged from the goose neck I have provided a booster fan 20, which draws preheated air through the pipe 21 from the checker chambers or slag pocket into the fan and forces it through the pipe 22 to the booster nozzle 23, terminating just inside the goose neck where it is discharged, thus affording a forced pressure on the gas and emitting from the gas nozzle a well directed and controlled flame. The pipes 21 and 22 extend to both ends of the furnace and are similarly connected, as best indicated in Fig. 1 which pipes are provided with suitable valves for making and breaking the operative connection with either end of the furnace as desired. As now shown in Figure 1, the valves are set so that the fan 20 is drawing preheated air from the left hand slag pocket and discharging it into the left hand booster nozzle, and from there into the left hand gas nozzle, while the pipes 21 and 22 leading to the right hand end of the furnace are closed. When the furnace is reversed the valves on the left hand side are closed and the ones on the right hand side contemporaneously open by merely moving the rod 24 in the proper direction. The gas nozzle is elliptical in cross section and made in different sizes, depending on the size of

the elliptical depression 11, in order to afford the best co-operation between these two members. Aside from eliminating entirely the gas and air ports, with my furnace by 5 having the ends practically open and comparatively no obstructions whatever in the way, the spent gases or products of combustion are readily and quickly discharged, thus making for the fast and sharp working of 10 the furnace.

I have successfully operated and demonstrated an open hearth, regenerative furnace embodying this invention and find from actual practice that it embodies to the fullest 15 extent, all of the foregoing and many other inherent advantages.

Having thus described my invention, I claim:

1. In an open hearth regenerative furnace, the combination of a block having 20 sides and bottom, a gas nozzle, so arranged as to cause the flame from the nozzle to impinge the sides and bottom of the intaking opening of said block.

2. In an open hearth regenerative furnace, the combination of an air uptake, a roofless conduit intermediate said uptake and the melting chamber, a gas nozzle arranged to discharge across the uptake and 30 into said conduit, and a booster nozzle for discharging fluid under major pressure into the gas nozzle.

3. In an open hearth regenerative furnace, the combination of a gas uptake, an 35 air uptake, and a melting chamber having canals extending to the air uptake and a source of flame pressure to direct the flame to the bottoms of said canals whereby air from the air uptake is diverted above the 40 flame.

4. In an open hearth regenerative furnace, the combination of a gas uptake, an air uptake, and a melting chamber having canals extending to the air uptake, each of which 45 has a sloping bottom with a raised portion subject to flame pressure, whereby air is excluded and operates to form a screen above the flame, and means for directing flame upon said raised portions.

5. In an open hearth regenerative furnace, the combination of a gas uptake, an air uptake, and a melting chamber having U-shape conduits leading to the air uptake, and means for directing a gas flame upon 55 the bottom and sides of the conduits.

6. In an open hearth regenerative furnace, the combination of a gas uptake, an air uptake, and a melting chamber having U-shape conduits leading to the air uptake, 60 and means for directing a gas flame upon the bottom and sides of the conduits to the substantial exclusion of air, which is thereby caused to seek a path above the flame.

7. The method of operating an open 65 hearth regenerative furnace, which consists

in directing the flame through substantially U-shape conduits in a manner to substantially exclude air from the bottom and sides of the conduit, and supplying air above the flame.

8. In an open hearth regenerative furnace wherein U shape conduits supply combustible media to the melting chamber, the method which consists in directing flame through said conduits and utilizing fluid to 75 hold the flame in its travel to substantially the bottoms and sides of the conduits.

9. In an open hearth regenerative furnace wherein U shape conduits supply combustible media to the melting chamber, the 80 method which consists in directing the flame downwardly and upon the sides of the conduits to substantially exclude air, and establishing an air barrier above the flame.

10. The method of operating an open 85 hearth regenerative furnace wherein combustible media is supplied to the melting chamber through open canals, which consists in flooding the canals with flame to the substantial exclusion of air, and introducing 90 a protective blanket of air above the flame.

11. An open hearth regenerative furnace, including the following elements, in combination, a melting chamber, an air uptake, a block provided with a cavity or depression ranging from the air uptake to the melting chamber, a gas nozzle adapted and arranged to discharge, under major pressure, across the air uptake and into and against the bottom and sides of the intake 100 portion of the cavity or depression, and means for imparting major pressure to the discharge from said nozzle.

12. An open hearth regenerative furnace, including the following elements, in combination, a melting chamber, an air uptake, a block provided with a cavity or depression ranging from the air uptake to the melting chamber, a gas nozzle having its end depressed whereby it is adapted to discharge 110 across the air uptake and into and against the bottom and sides of the intake portion of the cavity or depression, whereby air is compelled to travel above the flame, and means for imparting major pressure to the 115 discharge from said nozzle.

13. An open hearth regenerative furnace free from the usual supply ports, whereby it is of substantially open end construction, elements ranging crosswise the furnace and 120 having cavities leading to the melting chamber, means for supplying flame along said cavities, and means for supplying air above the flame.

14. An open hearth regenerative furnace 125 free from the usual supply ports, whereby it is substantially open at the ends, elements extending crosswise the open ends and having U shape passages leading to the melting 130 chamber, air and gas uptakes, and means

for introducing flame to said passages, the substantial exclusion of air from the air uptakes.

15. An open hearth regenerative furnace of substantially open end construction with relation to the melting chamber, elements extending crosswise thereof and having substantially U shape conduits leading to the melting chamber, said conduits having sloping bottoms, means for causing flame to travel along the bottom and sides of the conduits to the substantial exclusion of air, and means for supplying banks of air above the flame.

15 16. An open hearth regenerative furnace of substantially open end construction with relation to the melting chamber, elements extending crosswise thereof and having substantially U shape conduits leading to the melting chamber, said conduits having flaring ends, means for causing flame to travel along the bottom and sides of the conduits to the substantial exclusion of air, and means for utilizing air pressure to hold the flame upon the metal of the bath.

17. An open hearth regenerative furnace having air and gas uptakes, an open-top canal leading from said uptakes, and means for directing flame against the bottom of such canal, the canal bottom being formed to cause the flame to exclude air from such canal.

18. An open hearth regenerative furnace having air and gas uptakes, an open top canal leading from said uptakes, and means

for directing flame under pressure into and along such canal with the flame serving to exclude air from the canal.

19. An open hearth regenerative furnace having air and gas uptakes, means for delivering gas under pressure across the air uptake, and means for directing the flame of such gas to the melting chamber of the furnace under an overlying screen of air from the air uptakes.

45 20. An open hearth regenerative furnace having air and gas uptakes, means for delivering gas under pressure across the air uptake, and means for directing the flame of such gas to the melting chamber of the furnace under an overlying screen of air from the air uptakes, the flame cooperating with the directing means to exclude air therefrom during passage of the flame.

50 21. An open hearth regenerative furnace having air and gas uptakes, means for delivering flame under pressure across the air uptake and to the melting chamber of the furnace, and means for directing the flame under an overlying screen of air, the directing means being maintained clear of the direct passage of air by the passage of the flame therethrough.

In witness whereof I hereunto subscribe my name to this application in the presence of two witnesses.

WILLIAM MILLWARD.
